UNITED STATES PATENT OFFICE.

CHARLES H. THOMPSON, OF DETROIT, MICHIGAN.

DESIGN FOR A FRONT FRAME FOR VENDING APPARATUS.

SPECIFICATION forming part of Design No. 19,757, dated April 8, 1890.

Application filed February 25, 1890. Serial No. 341,752. Term of patent 7 years.

To all whom it may concern:

Be it known that I, CHARLES H. THOMPSON, of Detroit, in the county of Wayne and State of Michigan, have invented and produced a new and original Design for a Front Frame for Vending Apparatus, of which the following is a specification.

The object of this design is to provide a novel front frame for vending apparatus, as shown in the accompanying drawing, in which the figure is an elevation of the front frame showing my design.

In the drawing, the letters A A indicate the sides of the frame, which is approximately rectangular, slightly rounded at the top corners, and provided with upper and lower horizontal stiles b b, connected by a central vertical stile b², and comprising large rect-

angular panels G. A series of vertical stiles b' and numerous small rectangular panels G are arranged under the lowermost rail b, and beneath the smaller panels is a horizontal hood B, while under the latter is a rectangular part F.

The letter D indicates a key-hole, C C slots, and E knobs.

The frame presents the distinguishing appearance of a grid.

What I claim is—

The design for the front frame of a vending apparatus, substantially as shown and described.

CHARLES H. THOMPSON.
